UNITED STATES PATENT OFFICE.

MANUEL CARRANZA, OF HAVANA, CUBA.

DESIGN FOR A SPOON.

SPECIFICATION forming part of Design No. 21,256, dated December 22, 1891.

Application filed November 18, 1891. Serial No. 412,324. Term of patent 7 years.

To all whom it may concern:

Be it known that I, MANUEL CARRANZA, a citizen of Mexico, residing at Havana, Cuba, have invented and produced a new and original Design for a Spoon, of which the following is a specification, reference being had to the accompanying drawing, forming part thereof, which represents a spoon decorated in accordance with my design.

10 The leading feature of the design consists in the shape of the spoon-handle, which handle is formed to simulate a palm-tree, the trunk being prominent and the roots to an extent visible, and the leaves at the top of the 15 tree appearing gracefully bunched. The out-

line of the spoon-handle is therefore irregular, as the entire handle, as heretofore stated, is made to simulate a palm-tree.

The bowl of the spoon is represented as decorated with artistic lettering, reading "Re- 20 enero Habana," but I do not claim the same as a feature of the design.

I claim—

The design for a spoon, substantially as herein shown and described.

MANUEL CARRANZA.
